CONDUIT ADAPTER

John R. Madlem, Box 136A3 High Falls Road, R.D. 1,
Catskill, N.Y. 12414

Filed Mar. 26, 1974, Ser. No. 455,216

Term of patent 14 years

Int. Cl. D13—03; D23—01

U.S. Cl. D26—5 B

FIG. 1

FIG. 2

FIG. 3

FIG. 4

FIG. 6

FIG. 5

FIG. 7

FIG. 8

FIG. 1 is an isometric view from one end and above of my new design of a conduit adapter as shown in FIGS. 1 to 8;

FIG. 2 is an isometric view from the opposite end and above of my new design of conduit adapter as shown in FIGS. 1 and 8;

FIG. 3 is an end elevational view of my new design of conduit adapter seen in FIG. 1;

FIG. 4 is an end elevational view of my new design of conduit adapter shown in FIG. 2;

FIG. 5 is one side elevational view of my new design of conduit adapter viewed as shown in FIG. 3;

FIG. 6 is the other side elevational view of my new design of conduit adapter viewed as shown in FIG. 3;

FIG. 7 is a top plan view of my new design of conduit adapter viewed as shown in FIG. 3; and

FIG. 8 is a bottom plan view of my new design of conduit adapter viewed as shown in FIG. 3.

I claim:
The ornamental design of a conduit adapter, as shown.
